UNITED STATES PATENT OFFICE.

EDWARD G. WATKINS, OF GARDNER, MASSACHUSETTS.

DESIGN FOR A CHAIR-IRON.

SPECIFICATION forming part of Design No. 24,289, dated May 7, 1895.

Application filed April 6, 1895. Serial No. 544,823. Term of patent 14 years.

To all whom it may concern:

Be it known that I, EDWARD G. WATKINS, a citizen of the United States, residing at Gardner, in the county of Worcester and State of Massachusetts, have invented and produced a new and original Design for Chair-Irons, of which the following is a specification, reference being had to the accompanying drawings, showing a part thereof.

10 Figure 1 is a front elevation of a chair-iron, showing my design. Fig. 2 is a vertical sectional view of the same on the line 2 2 of Fig. 1, these two views being deemed necessary to fully illustrate my design.

15 The leading features of my design consist in a chair iron of a general polygonal shape provided at one end with a plug (a²) and at its other end with a plate (a') joined together by standards (a⁶) integral with said plate and plug, but spaced from one another, said plate and plug being provided with apertures, the sides of the aperture in said plug being formed with symmetrically arranged projections.

20 (a) represents the chair iron which consists 25 of the plate (a') provided with an aperture

(a³). At its opposite end this casting is provided with a plug (a²) apertured as at (a⁴), the sides of this aperture (a⁴) being formed with symmetrically arranged projections (a⁵). The plate and plug are joined together by 30 angular shaped standards (a⁶) integral with said parts, but spaced from one another, thus forming a compartment (a⁸) between the plate and plug, and leaving openings (a⁷) between contiguous standards (a⁶). The top of the 35 plate is formed with fanciful curved lines (a⁹). The chair iron is of general polygonal form and is neat and attractive in appearance.

What I claim is—

The design for a chair iron, substantially 40 as set forth.

In testimony whereof I have signed my name to this specification, in the presence of two subscribing witnesses, this 4th day of April, A. D. 1895.

EDWARD G. WATKINS.

Witnesses:

A. D. HARRISON,
ROLLIN ABELL.
